CLAIM

The ornamental design for a crossbow arrow retainer, as shown and described.

DESCRIPTION

FIG. 1 is a top perspective view of a crossbow arrow retainer, showing my new design;

FIG. 2 is a top plan view thereof;

FIG. 3 is a bottom plan view thereof;

FIG. 4 is a front elevation view thereof;

FIG. 5 is a back elevation view thereof;

FIG. 6 is a left side elevation view thereof; and,

FIG. 7 is a right side elevation view thereof.

The broken lines in the Figures represent environmental structure or unclaimed portions of the device and are for illustrative purposes only. The broken lines form no portion of the claimed design.
